St. L. Carroll
Gerald Henney

UNITED STATES PATENT OFFICE.

WILL YERGER, OF PHILADELPHIA, PENNSYLVANIA.

PACKAGE TIE.

Application filed October 11, 1924. Serial No. 743,045.

To all whom it may concern:

Be it known that I, WILL YERGER, a citizen of the United States, residing at Philadelphia, in the county of Philadelphia and 5 State of Pennsylvania, have invented new and useful Improvements in Package Ties, of which the following is a specification.

This invention relates to improvements in package ties for securing packages of mail 10 matter, merchandise and the like, and is an extensive improvement on the package tie as disclosed by my Patent No. 1,357,134.

The primary object of this invention is to provide a package tie designed for use in 15 the Post Office Department and like service, to be used in the place of binding twine for tying packages of mail or merchandise to be sent to substations or other desired places.

20 Another object is to provide a package tie which prevents the cord thereof from becoming entangled and knotted when not in use, the cord being adequately protected to prevent this danger.

25 A further object is to provide a package tie that will hold securely one or more letters and the like, and can be used with equal facilities by either a right or left handed operator, without instructions as to 30 its use, the device being extremely simple, yet efficient for the purpose intended.

This invention also consists in certain 35 other features of construction and in the combination and arrangement of the several parts, to be hereinafter fully described, illustrated in the accompanying drawings and specifically pointed out in the appended claims.

In describing my invention in detail, reference will be had to the accompanying 40 drawings wherein like characters denote like or corresponding parts throughout the several views, and in which:—

Figure 1 is a perspective view showing a 45 package tied by my improved device.

Figure 2 is a transverse sectional view through the package tie per se.

Figure 3 is a top plan view showing the 50 means for receiving the cord, which is illustrated by dotted lines.

Referring to the drawings in detail the letter A indicates a package tied by the package tie forming the subject matter of the present invention.

55 The cord 1 when not extended for tying purposes as well as that portion of the cord

which is not in use when the package tie is in operative position as shown in Figure 1, is housed in the casing 2 which consists of a lower cup shaped portion 3 having its upper outer edge screw threaded for receiving the cover 4 as shown. The cover 4 is provided with a centrally disposed opening 5 to provide a bearing surface for a portion of the shank of a screw 6 which is provided 60 with a knurled head 7 whose under portion is provided with a cam surface 8 operatively associated with the cover 4, for a purpose which will be presently described. The greater portion of the shank of the screw 65 is threaded for receiving a reel 9 which is secured to the shank to turn with the screw, in the bearing formed in the cover for the shank.

The reel is solid and a bore 10 is formed 75 therethrough adjacent one side of the central portion thereof, one end of the bore has its outer edge rounded as at 11 to prevent damage to the cord 1 which is adapted to be passed through the bore and have one 80 end knotted which is received in the recess 12 disposed at the opposite end of the bore 10 as clearly disclosed in Figure 3 of the drawings. The cord extends from the casing through the medium of an opening 13 85 formed in the side walls of the cup shaped portion 3.

The operation of the device forming the subject matter of the present invention is extremely simple and is suggested by the 90 drawings. The cord 1 is secured to the reel as above set forth and is payed off as desired, depending of course upon the amount to be used for tying a predetermined size 95 package. The reel is under tension by the frictional engagement the cover and the cup shaped portion 3 contacting the upper and lower surface thereof, and this tension may be varied by adjusting the cover through the medium of its screw threaded 100 connection with the cup shaped portion. The payed out cord is then arranged around the package in the usual manner and the free end of the cord secured by engagement with the cam surface of the screw head and the cover as suggested in Figure 105 1 of the drawings. If the cord is too loose after the above operation is performed the screw can be turned to take up slack.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A package tie of the character described comprising a casing provided with an opening formed in its side wall, a reel 10 mounted for frictional rotatable movement within the casing, and a cord secured to the reel and passing through the opening as and for the purpose specified.
2. A package tie of the character described comprising a casing, a reel rotatably mounted therein, a headed screw secured to the reel for the operation thereof and being provided with a cam surface, the cord secured to the reel and adapted to have its free 20 end operatively associated with the cam sur-

face and casing respectively as and for the purpose specified.

3. A package tie of the character described comprising a casing, a cup shaped portion included therein, and being provided with an opening formed in its side wall, the cover for the cup shaped portion being provided with a centrally disposed opening forming the bearing, a headed screw having a portion of its shank threaded and its remaining portion arranged in the bearing for rotatable movement, a reel in the casing and receiving the threaded end of the shank to be rotated thereby, and a cord secured to the reel and passed through the opening in the side wall for operative association with the screw and cover.

In testimony whereof I affix my signature.

WILL YERGER.
